UNITED STATES PATENT OFFICE.

DANIEL S. WAUGH, OF DENVER, COLORADO, ASSIGNOR, BY MESNE ASSIGNMENTS, TO THE DENVER ROCK DRILL MANUFACTURING COMPANY, A CORPORATION OF DELAWARE.

DRILL-ROTATING MECHANISM.

1,081,351.

Specification of Letters Patent.

Patented Dec. 16, 1913.

Application filed February 20, 1913. Serial No. 749,758.

To all whom it may concern:

Be it known that I, DANIEL S. WAUGH, a citizen of the United States, residing at Denver, in the county of Denver and State of Colorado, have invented new and useful Improvements in Drill-Rotating Mechanism, of which the following is a specification.

The object of the present invention is to 10 provide simple means of an effective character for effecting the automatic rotation of a drill bit from the piston, said means being very compact in its character, and thus making the drilling apparatus, as a whole, 15 relatively short.

An embodiment of the invention that is at present considered the preferable one, is illustrated in the accompanying drawings, wherein:—

20 Figure 1 is a longitudinal sectional view through a portion of a hammer drill, showing the improved rotating mechanism. Figs. 2 and 3 are respectively, cross sectional views on the lines 2—2 and 3—3 of Fig. 1. 25 Fig. 4 is a sectional view through the ratchet ring. Fig. 5 is a perspective view of the piston and tappet. Fig. 6 is a similar view of the chuck-rotating ring. Fig. 7 is a detail perspective view of the inner end of the 30 chuck sleeve, and Fig. 8 is a perspective view of the ratchet ring, with a portion thereof broken away.

Similar reference numerals designate corresponding parts in all the figures of the 35 drawings.

In the embodiment disclosed, a portion of the cylinder member is illustrated, and is designated 9. This cylinder member is provided at one end with a casing 10, having a 40 barrel extension 11. Within the said barrel extension is a rotatable chuck comprising a sleeve 12 having at its inner end an outstanding retaining flange 13 that abuts against the inner end of the barrel 11, and 45 provided in its outer end with a chuck bushing 13', said bushing having a drill-bit receiving socket 14 that is angular in cross section to correspond to the particular cross sectional shape of the drill-bit. Thus, in 50 the present embodiment, a portion of a hexagonal bit 15 is shown. The sleeve 12 has a bore 16 at its inner end that communicates with a counterbore 17, in which the bushing 13' is placed and suitably secured. A recip-

rocatory tappet 18 is located in the chuck sleeve between the ends thereof, said tappet having its main portion 19 slidably fitted in the bore 16, and having an enlarged head portion 20 operating in the counterbore.

A reciprocating piston 21 operates in the cylinder member 9, and is driven by fluid under pressure controlled by any suitable means. This piston 21 is provided with a reduced hammer extension 22 that has a bearing in the inner end portion 23 of the 65 casing 10, said hammer extension passing through the casing and slidably operating in the inner end of the chuck sleeve 12 in a position to strike the tappet 19. This hammer extension 22 is provided with oppositely arranged spiral grooves or ways 24, and between said grooves or ways is also provided with longitudinal grooves or ways 25.

Rotatably mounted in the casing 10 is a 75 chuck-turning ring 26, which, as shown more particularly in Fig. 6, is provided with rear arcuate extensions 27, provided on their inner sides with feathers or keys 28 that are slidably engaged in the longitudinal guide- 80 ways 25. The outer face of this ring has notches 29 that receive lugs 30 formed on the inner end of the chuck sleeve 12. It will thus be evident that the ring 26 constitutes a connection between the piston and 85 the chuck that prevents their relative rotation, or in other words, secures their simultaneous rotation.

Surrounding the extensions 27 of the ring 26 is a ratchet wheel or ring 31 provided 90 with peripheral ratchet teeth 32, and having on its interior, inwardly extending spiral keys or feathers 33 that are engaged in the spiral ways or grooves 24 of the hammer extension of the piston, the feathers 33, 95 as shown in Fig. 2, being located between the feathers 28 of the ring 26. The casing 10 is provided with opposite enlargements 34 having sockets 35 for the reception of pivot enlargements 36 of swinging pawls 37 100 that engage the peripheral teeth 32 of the ratchet ring to prevent its rotation in one direction. Hollow plugs 38, threaded into the enlargements 34 of the casing, contain 105 slideable plungers 39 that bear against these pawls 37, and are yieldingly held against the same by springs 40, also located in said plugs.

Briefly described, the operation of the mechanism is as follows: When the piston moves forwardly, it will give a left hand rotative motion to the ratchet ring, causing it to rotate in a direction to carry one or more teeth past the pawls 37. Upon the backward movement of the piston, however, the said pawls prevent a retrograde rotation of the ratchet ring, and as a consequence, the piston must turn. As it turns, it turns the chuck with it through the medium of the ring 26, and consequently, causes a partial rotation of the drill bit in said chuck. Therefore as the piston reciprocates, a step-by-step rotation of the same occurs, and a corresponding step-by-step rotation of the chuck and drill bit takes place.

From the foregoing, it is thought that the construction, operation and many advantages of the herein described invention will be apparent to those skilled in the art, without further description, and it will be understood that various changes in the size, shape, proportion, and minor details of construction may be resorted to without departing from the spirit or sacrificing any of the advantages of the invention.

Having thus fully described my invention, what I claim as new, and desire to secure by Letters Patent, is:—

1. In apparatus of the character described, the combination with a cylinder member and a reciprocatory piston operating therein, of a rotatable tool-holding chuck, a rotatable ring detachably interlocked with the front end of the piston and the rear end of the chuck, and means for rotating the piston.

2. In apparatus of the character described, the combination with a cylinder member and a reciprocatory piston operating therein, of a rotatable tool-holding chuck, a rotatable ring detachably interlocked with the front end of the piston and the rear end of the chuck, and means interlocked with the front end of the piston for effecting a step-by-step rotation of said piston.

3. In apparatus of the character described, the combination with a cylinder member and a reciprocatory piston operating therein, of a rotatable chuck, a pair of rotatable rings, one being mounted on the other, one of said rings being connected to the chuck and piston, the other to the piston only, and means for effecting a step-by-step rotation of the latter ring.

4. In apparatus of the character described, the combination with a cylinder member and a reciprocatory piston operating therein, of a rotatable chuck, a rotatable ring detachably interlocked with the rear end of the chuck and having extending portions slidably interlocked with the piston,

and a ratchet ring rotatable on said extended portions and slidably interlocked with the piston.

5. In apparatus of the character described, the combination with a cylinder member and a reciprocatory piston operating therein, of a rotatable chuck, a rotatable ring, said ring and chuck being provided, one with sockets and the other with lugs engaged in the sockets, said ring being also provided with spaced extensions slidably interlocked with the piston, and a ratchet ring surrounding the extensions and having portions arranged between the same and slidably interlocked with the piston.

6. In apparatus of the character described, the combination with a cylinder member and a rotatable chuck, of a reciprocatory piston, and means for rotating the chuck, including relatively rotatable rings, one engaged with the chuck and the other with the piston.

7. In apparatus of the character described, the combination with a cylinder member and a rotatable chuck, of a reciprocatory piston, and means for rotating the chuck, including relatively rotatable rings, both slidably engaged with the piston, and one being connected to the chuck.

8. In apparatus of the character described, the combination with a cylinder member and a rotatable chuck, of a reciprocatory piston, and means for rotating the chuck, including relatively rotatable concentric rings, both slidably interlocked with the piston, and one being connected to the chuck.

9. In apparatus of the character described, the combination with a cylinder member and a rotatable chuck mounted thereon, of a reciprocatory piston having a hammer extension that enters the inner end of the chuck, said extension having longitudinal and spiral grooves, a ring interlocked with the longitudinal grooves and with the chuck, a ratchet ring rotatably associated with the first mentioned ring and having feathers engaged in the spiral grooves, and a dog co-operating with the teeth of the ratchet wheel.

10. In apparatus of the character described, the combination with a cylinder member and a piston operating therein, of a rotatable chuck, and means for effecting a rotation of the chuck from the piston, said means including a pair of relatively rotatable rings, one having portions mounted within the other and both having angularly disposed parts slidably interlocked with the piston.

11. In apparatus of the character described, the combination with a cylinder member and a piston operating therein, of a rotatable chuck, and means for effecting a rotation of the chuck from the piston, said

means including a pair of relatively rotatable rings, one of said rings having inwardly extending feather elements slidably interlocked with the piston, the other ring having feather elements located within the first-
5 mentioned ring between the feather elements thereof and also slidably interlocked with the piston.

12. In apparatus of the character de-
10 scribed, the combination with a cylinder member and a piston operating therein having longitudinal and spiral grooves, of a rotatable chuck, and means for rotating the chuck from the piston, said means includ-
15 ing a pair of relatively rotatable rings, one having portions mounted within the other, said rings having angularly disposed feather elements respectively engaged in the longitudinal and spiral grooves of the piston.

20 13. In apparatus of the character de-
scribed, the combination with a cylinder member and a piston operating therein, of a rotatable chuck, and means for effecting the rotation of the chuck from the piston, said
25 means including a pair of relatively rotatable rings, one of the rings being engaged with the rear end of the chuck and having portions located within the other ring, said

portions being provided with feather ele-
ments slidably interlocked with the piston, 30 the other ring also having inwardly extending feather portions that are slidably interlocked with the piston.

14. In apparatus of the character de-
35 scribed, the combination with a cylinder member and a reciprocatory piston therein, having longitudinal and spiral grooves, of a rotatable chuck, a ring surrounding the pis-
30 ton and having inwardly extending feather elements slidably engaged in one set of 40 grooves, and another ring engaging the rear end of the chuck and having rearwardly extending portions located within the first-mentioned ring between the feather ele-
45 ments thereof, said portions being also pro-
vided with inwardly extending feather ele-
ments slidably engaged in the other set of grooves of the piston.

In testimony whereof I have hereunto set
my hand in presence of two subscribing wit-
50 nesses.

DANIEL S. WAUGH.
